UNITED STATES PATENT OFFICE.

WILLIAM BEHL, OF SCOTLAND, SOUTH DAKOTA.

EAVES-STRIP.

No. 873,407.

Specification of Letters Patent

Patented Dec. 10, 1907.

Application filed August 24, 1907. Serial No. 390,013.

To all whom it may concern:

Be it known that I, WILLIAM BEHL, citizen of the United States, residing at Scotland, in the county of Bonhomme and State of South Dakota, have invented certain new and useful Improvements in Eaves-Strips, of which the following is a specification.

This invention has for its object an improved eaves strip designed to securely fasten down to the ordinary sheathing the waterproofing material such as tarred paper or other sheets of suitable material, and designed also to project over the edge of the roof to effectively shed the water into the eaves-trough and the invention consists in certain constructions and arrangements of the parts that I shall hereinafter fully describe, and then point out the novel features in the appended claims.

20 For a full understanding of the invention, reference is to be had to the following description and accompanying drawings, in which:

Figure 1 is a sectional perspective view of my improved eaves strip, showing it applied; and Fig. 2 is a transverse sectional view thereof.

Corresponding and like parts are referred to in the following description and indicated in all the views of the drawings by the same reference characters.

Referring to the drawings, the numeral 1 designates the ordinary sheathing of a roof, and 2 designates the sheets of paper or waterproofing composition.

My improved eaves-trough consists of an integral or continuous strip 3 of metal preferably formed into the requisite shape at the shop ready to apply, said strip being twice doubled upon itself along its rear edge to form the rearwardly facing pocket 4 receiving the front edge of the waterproofing strip or sheet 2. Nails or other fastening devices are driven through the several plies of metal, 45 and penetrate the sheathing 1, to hold the parts together, as clearly illustrated at 5.

From the pocket 4, the metal strip 3 extends forwardly, sloping as shown, so as to project beyond the roof, the said strip being curled backwardly and upwardly to the bib 7, then being extended rearwardly, and provided with an angularly disposed, down-

wardly bent edge 9 which is secured to the front edge of the sheathing and which preferably projects below the latter so as to protect the joint between the sheathing and the wall. 10 designates the eaves-trough over which the eaves strip extends, so as to effectively shed the water into the trough.

From the foregoing description in connection with the accompanying drawings, it will be seen that I have provided a durable and efficient construction of eaves strip which will protect the joint between the sheathing of the roof and the wall of the building, which will afford an effective watershed from the roof into the eaves-trough, and which will provide means for securely holding the waterproofing sheets.

Having thus described the invention, what is claimed as new is:

1. The herein described eaves strip formed with a rearwardly facing pocket and extending forwardly therefrom, said strip being curled upon itself along an intermediate line and thence returned upon itself and provided with a downwardly extending opposite edge portion, substantially as described.

2. The herein described eaves strip, consisting of an integral or continuous structure twice doubled upon itself at one edge to form a rearwardly facing pocket, said strip extending forwardly from said pocket and thence downwardly and backwardly and provided with a downwardly extending opposite edge portion.

3. The combination with the sheathing of a roof, of a continuous eaves strip doubled upon itself along one edge to form a pocket and secured at such edge to the sheathing, said strip extending forwardly beyond the sheathing and provided with a bib, the said strip extending rearwardly from the bib and provided with a downwardly extending opposite edge portion secured to the front edge of the sheathing, such edge portion projecting below the sheathing.

In testimony whereof I affix my signature in presence of two witnesses.

WILLIAM BEHL. [L. s.]
